CIGARETTE ROLLING DEVICE

Sidney A. Getts, Jr., Rockford, Ill.

Application August 23, 1945, Serial No. 612,236

5 Claims. (Cl. 131—58)

1

This invention relates to cigarette rolling devices, and one object is to utilize for this purpose a tube slotted along one side and having a flange for leading the paper into the slot.

A more detailed object is to provide a slotted and flanged tube of the above character together with a plug adapted to be received in the end of the tube and used to roll a cigarette paper along the flange and around the interior of the tube.

Another object of the invention is to provide an improved rolling device which incorporates a holder on which the cigarette is rolled.

A still further object is to provide a rolling device incorporating a cigarette holder wherein the holder serves an additional function in forming the cigarette.

Other objects and advantages will become apparent from the following description of one illustrative device embodying the invention and shown in the accompanying drawing, in which

Fig. 1 is a perspective view illustrating the method of rolling a cigarette;

Fig. 2 is a perspective view of the completed cigarette with the holder incorporated therein;

Fig. 3 is an exploded perspective view of the device showing the respective elements in relative position;

Fig. 4 is an enlarged fragmentary perspective view showing the paper receiving slot in the rolling tube;

Fig. 5 is a section taken on the plane 5—5 of Fig. 6;

Fig. 6 is a longitudinal section of the device; and

Fig. 7 is a similar longitudinal section showing a different means for introducing tobacco into the device.

My improved rolling device comprises generally a tube 15, preferably rolled from one end portion of a piece of sheet metal and having a straight slot 16 along one side defined by one end edge 15a of the metal piece coacting with the surface of a flange 17 formed by the other end portion of the metal piece and projecting tangentially from the slot. The tube is somewhat longer than the cigarette to be formed.

A cigarette paper laid in the flange 17 with one edge or corner projecting into the slot adjacent the end thereof is guided into the tube and around the interior thereof to form a paper cylinder. Such rolling may be effected by a plug 10, one end of which is loosely received in one end of the tube and has an external surface 12 whose coefficient of friction is somewhat greater

than that of the tube material, so as to grip the cigarette paper and advance it along the flange and tube surfaces. The friction surface may advantageously be formed by a relatively soft rubber sleeve 13 surrounding the tip 14 of the holder and therefore out of contact with the smoke passing through the bore of the holder.

By forming a hole through the plug 10 and shaping the end 11 thereof so that it may be held in the user's mouth, the plug may be used as a holder for the cigarette during smoking of the latter.

In forming a cigarette, a paper (with the gummed edge 18 upward, if a gummed paper be used) is laid on the guide 17 and thereby introduced edgewise through the slot into the tube. In the present case the tube comprises a metal sheet rolled into tubular form with one edge forming an edge of the slot 16 and the opposite margin being bent at an angle to the tube to form the guide 17. One of the leading corners of the paper engages the friction surface 12 of the holder 10 which previously has been inserted into the tube (see Fig. 1). By rotating the holder in the tube the paper is drawn edgewise into the tube and curled around by the tube to form a cylindrical paper wrapper. Before the trailing edge of the paper enters the tube, it is moistened to cement the edge to the paper cylinder in the customary fashion. The small clearance between the friction surface 12 in the tube insures adequate traction on the paper for the aforesaid purpose and also insures that the paper will be wrapped around the holder sufficiently tightly to incorporate the holder in the cigarette. Also the holder by firmly supporting the end of the cylindrical wrapper gives the latter sufficient rigidity to press the sealing edge of the wrapper against the underlying paper firmly enough to cement the edge in place. For this purpose the wrapper may be rotated several times inside the tube.

After the paper cylinder 19 has been formed tobacco is introduced into the opposite open end 45 of the tube which for that purpose is provided with an extension 20 projecting beyond the end of the paper cylinder. In this case the projection simply comprises an elongation of the tube with the flange 17 cut away at this point (see Fig. 4). Tobacco may be introduced in various ways. For example, a fitting 21 having a groove 22 therein, may be inserted into the tube. A tobacco container such as a tobacco sack 23 may be fastened to the fitting by the neck of the sack 50 into groove 22 by means of the draw strings on

the sack, thereby providing a convenient means for directing tobacco into the interior of the paper tube.

Fig. 7 illustrates one alternative device for introducing tobacco into the tube. Such device is in the form of a funnel 24 inserted in the tube 15. The funnel end of the fitting is adapted to receive tobacco which flows into the interior of the paper cylinder. These fittings may advantageously be provided with a tip 25 of reduced diameter which enters the interior of the paper cylinder 19 and thus protects the end of the cylinder from crumpling when the tobacco is introduced. Tapping of the cylinder serves to accelerate flow of the tobacco and to pack it in the cigarette.

After introduction of the tobacco, the completed cigarette is withdrawn by means of the holder which is then used for smoking the cigarette. If desired, the outer end of the paper cylinder may be twisted to close it. The holder of course prevents escape of tobacco into the mouth. After smoking, the holder is recovered and used for the next cigarette.

Obviously, the invention is not limited to the details of the illustrative device, since these may be variously modified. Moreover, it is not indispensable that all features of the invention be used conjointly since various features may be used to advantage in different combinations and subcombinations.

I claim as my invention:

1. A cigarette rolling device comprising, in combination, a rolling tube having a slot therein for edgewise reception of a cigarette paper, a rotatable cigarette holder having a friction surface adapted to be inserted in an end of the tube to engage a portion of the paper to draw the latter into the tube to form a cylindrical paper wrapper therein, and means for introducing tobacco into the wrapper.

2. A cigarette rolling device comprising, in combination, an open ended rolling tube having a slot therein for edgewise reception of a cigarette paper, a rotatable cigarette holder having a friction surface inside said tube of a diameter slightly less than the internal diameter of the tube and adapted to engage a corner of the paper between it and the tube and on rotation of the holder to draw the paper into the tube to form a cylindrical wrapper, and means for introducing tobacco into the wrapper.

3. A cigarette rolling device comprising, in combination, a rolling tube having a slot therein for edgewise reception of a cigarette paper and having a flange adjacent an edge of the slot to guide the paper edgewise through the slot into the tube, a cigarette holder rotatable in one end

of the tube and having a surface for frictionally engaging the leading corner of the paper and drawing the latter into the tube on rotation of the holder to wrap the paper tightly around said surface on the holder to form a cylindrical wrapper, and a fitting on the other end of the tube for introducing tobacco into said wrapper, said wrapper being longitudinally slidable in said tube and being attached to said holder so that the completed cigarette may be withdrawn from the tube by said holder.

4. A cigarette rolling device comprising, in combination, a rolling tube having a slot therein for edgewise reception of a cigarette paper and having a flange adjacent an edge of the slot to guide the paper edgewise through the slot into the tube, a cigarette holder rotatable in one end of the tube and having a surface for frictionally engaging the leading corner of the paper and drawing the latter into the tube on rotation of the holder to wrap the paper tightly around said surface on the holder to form a cylindrical wrapper, and a fitting on the other end of the tube for introducing tobacco into said wrapper and having a tip projecting slightly inside the end of said wrapper to protect the latter during introduction of the tobacco.

5. A cigarette rolling device comprising, in combination, a tube formed of sheet metal bent to a substantially circular cylindrical form with one margin bent at an angle to the tube and the opposite edge being separated from said margin to form a slot for edgewise reception of a cigarette paper, a cigarette holder rotatable in one end of the tube and having a surface for frictionally engaging the leading corner of the paper and drawing the latter into the tube on rotation of the holder to wrap the paper tightly around said surface on the holder and to form a cylindrical wrapper, said surface being smaller than the internal diameter of the tube by substantially the thickness of the wrapper around said surface, and means for introducing tobacco into the other end of the tube.
